French Eugene Smith, Akron, Ohio, assignor to Imperial Glass Corporation, Bellaire, Ohio, a corporation of Ohio

Application February 24, 1953, Serial No. 23,762

Term of patent 14 years

(Cl. D36—8)

To all whom it may concern:

Be it known that I, French Eugene Smith, a citizen of the United States, residing at Akron, county of Summit, and State of Ohio, have invented a new, original, and ornamental Design for a Tumbler or Similar Article, of which the following is a specification, reference being had to the accompanying drawing, forming a part hereof, in which

Figure 1 is a side elevational view of a tumbler or similar article, showing my new design;

I claim:

The ornamental design for a tumbler or similar article, substantially as shown.
